UNITED STATES PATENT OFFICE

GEORGE W. PIGGOTT, OF NEW YORK, N. Y., ASSIGNOR TO HARTFORD CARPET COMPANY, OF HARTFORD, CONN.

DESIGN FOR CARPET.

Specification forming part of Design No. **11,402**, dated September 9, 1879; application filed August 2, 1879.
[Term of patent 3½ years.]

To all whom it may concern:

Be it known that I, GEORGE W. PIGGOTT, of New York city, county and State of New York, have invented a new and original Design for a Carpet, of which the following is a specification.

The accompanying photograph illustrates my new design.

This invention relates to a new design for carpets, oil-cloths, and analogous fabrics; and consists in the novel grouping and configuration of figures, hereinafter more fully pointed out.

Upon the background is represented a straight bar, *a*, having a rectangular corner-piece, *b*, at one end thereof and contiguous thereto. *g* is another straight bar, and *f* an angle-piece, placed at a distance therefrom, and having one of its wings parallel to the bar *g*.

Between and around these bars and corner-pieces are represented rich floral ornamentations, consisting of leaves and of flowers of

various forms, among which the flowers *d* and *e* are conspicuous.

The whole constitutes an attractive and rich design.

I claim—

1. The design for a carpet, consisting of the bar *a* and the contiguous corner-piece *b*, substantially as shown.
2. The design for a carpet, consisting of the bar *g*, corner-piece *f*, and intermediate leaves, substantially as shown.
3. The design for a carpet, consisting of the bars *a g*, corner-pieces *b f*, and intermediate leaves, substantially as shown.
4. The design for a carpet, consisting of the bars *a g*, corner-pieces *b f*, flowers *d e*, and intermediate leaves, substantially as shown.

GEO. W. PIGGOTT.
